UNITED STATES PATENT OFFICE

GÜNTHER KEITEL, OF NEW YORK, N. Y.

COLLAR-SUPPORT.

No. 900,932.

Specification of Letters Patent.

Patented Oct. 13, 1908.

Application filed May 13, 1908. Serial No. 432,585.

REISSUED

To all whom it may concern:

Be it known that I, GÜNTHER KEITEL, a citizen of the United States, residing in New York city, in the county of New York and State of New York, have invented certain new and useful Improvements in Collar-Supports, of which the following is a specification.

This invention relates to stiffeners for garments and is especially designed for use with collars used by women, and it is of special advantage where the collar is of considerable height, but of comparatively thin and weak material that would not of itself retain its upright position.

The object of the invention is to provide an improved form of stiffener that can be very readily and economically made, and which will be composed of a pocket member that can be washed when desired, and of a removable rigid resilient material that can be readily removed from the pocket without removal of any stitches or without in any way interfering with the construction of the pocket member but by merely bending the article, and which can be returned to the pocket member after it has been washed by merely bending to permit the insertion of the ends and then slipping the stiffener member into the pockets.

In the accompanying drawings representing one embodiment of my invention Figure 1 shows in elevation, a collar with my invention applied thereto. Fig. 2 is a plan view of the stiffener. Fig. 3 is a longitudinal section of the device; and Fig. 4 is a similar section with the pocket member bent somewhat upon itself to the position for insertion and removal of the stay member.

The invention comprises two members a pocket member and a stay member. The pocket member is formed of any suitable pliable material preferably of fabric such as muslin, linen, silk or tape. In the construction illustrated it is formed of a long narrow strip *a* having the end portions *b* and *c* doubled upon themselves as indicated in Fig. 3. Thereupon the margins at *f* and *g* and also at *h* and *k* at the opposite sides of the lapped strips are secured together in any suitable manner, preferably by stitching *s*. These side strips form two pockets *d* and *e* having their openings at *m* and *n* respectively that are opposite each other. The other member of the stiffener comprises a stay *T* formed of a strip of comparatively rigid but resilient material

such as whale-bone, or steel or celluloid, or wood of some nature, or any similar material that is sufficiently elastic to bend without breaking for insertion or removal. 60 The pocket member is then bent somewhat U-shaped as indicated in Fig. 4, and the resilient strip is bent similarly to permit its ends *w* and *x* to enter the pockets at *m* and *n*, as shown. The stay is then pushed into the 65 pockets, and the device permitted to straighten out as shown in Figs. 2 and 3; the stay being of sufficient length to completely fill the pockets in the straight normal condition. The overlapping ends *c* and *b* preferably have their end portions at *p* and *r* bent upon themselves again as indicated in Fig. 3, to prevent the ends from raveling out and to better protect them. The stitching *s* is preferably carried across the extremities at *y* and 75 *z* as indicated. In fact the line of stitching can be continuous around the margin of the entire pocket member as shown in Fig. 2.

By this construction it will be seen that a stiffener is formed by which it is very easy to 80 remove the stay member upon simply bending the stiffener as indicated in Fig. 4 and pulling out the ends of the strip. This will permit the fabric or pocket portion to be washed whenever desired and then when dry 85 the stay can be returned to its former position. Or should the stay break it can be easily removed and another one substituted. It will be further seen that the device is very 90 simple of construction and manufacture. 90 The fabric being simply a long strip, that might be a piece of tape or the like, with the ends doubled upon itself as set forth, and secured by the line of stitching to form the pockets. Thereupon the stay member is 95 readily inserted by merely bending the two members as described.

This stiffener can be very easily secured to a collar by sewing along the margins, as indicated in Fig. 1. This stiffener member can 100 obviously be made in any size desired and can be used in any part of a garment where it might be useful.

Having thus described my invention, I claim:

1. As an article of manufacture, a stiffener comprising a stay member formed of a strip of resilient material, and a narrow strip of fabric extending the full length of the stay and provided at its end portions with pockets, the outer ends of such pockets being closed and spaced apart a distance substan-

tially equal to the length of the stay, while the inner opposite ends are open for the insertion of the stay, whereby the stiffener may be attached to a base fabric, with the stay out of contact with said base fabric.

2. As an article of manufacture, a stiffener for attachment to garments comprising a strip of resilient material and a narrow strip of fabric extending the full length of the stay and having each end portion doubled upon

itself with the side edges secured together to form spaced pockets open at the inner opposite ends for the insertion of the stay, whereby the stiffener may be attached to a base fabric with the stay out of contact with said base fabric.

GÜNTHER KEITEL.
